UNITED STATES PATENT OFFICE

HERBERT G. BEEDE, OF PAWTUCKET, RHODE ISLAND, ASSIGNOR TO PANTEX PRESSING MACHINE, INC., OF PAWTUCKET, RHODE ISLAND, A CORPORATION OF DELAWARE

STEAMING BOARD

Original application filed November 26, 1928, Serial No. 322,011. Divided and this application filed February 3, 1930. Serial No. 425,512.

This invention relates to a steaming board adapted to be used individually or in connection with a garment pressing machine for applying steam to the garment or other fabric upon or in proximity to the surface of the steaming board for moistening and softening said garment or fabric preparatory to pressing, shaping or other treatment thereof as set forth in my pending application Serial No. 322,011, filed November 26, 1928, of which this application is a division.

The invention also contemplates means for expeditiously removing the moisture from the garment or other fabric following the moistening, pressing and shaping operations for drying purposes.

These steaming boards when used in connection with garment pressing machines of the class set forth in my Patent No. 1,661,153, dated March 6, 1928, are commonly known as bucks but when used individually or in connection with the pressing machine they are preferably provided with a heating chamber and a steam distributing chamber, the heating chamber being constantly supplied with steam for maintaining a proper temperature of the buck or steaming element while the distributing chamber is preferably supplied with steam from some available source of supply at the will of the operator and is provided with steam exits through its top wall for liberating the steam to the garment or fabric on the upper surface of the steaming element.

One of the objects of the invention, however, is to divide this distributing chamber into separate compartments and to provide simple and efficient means under the control of the operator whereby the steam may be distributed through the surfaces of all of the compartments simultaneously or through the surface of one of the compartments independently of the others thus permitting economic conservation of the steam, particularly when operating upon small garments or small portions of large garments when only a relatively small portion of the surface area of the steaming element is required.

A further object is to provide simple and

efficient means under the control of the operator for withdrawing the steam and moisture from the surfaces of all of the compartments simultaneously or from the surface of one of the compartments only according to the nature of the work operated upon for moistening purposes. 55

The supply of steam to the plural compartments is controlled by one valve while the supply of steam to one of the compartments 60 may be cut off by another valve and the exhaust of the steam from all or one of the compartments is controlled by a third valve and all of these three valves are controlled by separate pedals through the medium of separate 65 connections hereinafter more fully described and one of the objects of the present invention is to construct and assemble these pedals in such manner that they may be individually operated in the same order from either 70 side of the machine without necessitating the changing of position of the operator.

Another object is to enable the pedal which controls the cut-out valve for one of the compartments to be operated simultaneously with 75 either the steam controlling pedal or the exhaust controlling pedal.

Other objects and uses relating to specific parts of the machine will be brought out in the following description. 80

In the drawings:

Figure 1 is a side elevation, partly in section, of a fabric moistening and drying machine embodying the various features of my invention. 85

Figure 2 is a horizontal sectional view of the steaming board or buck taken in the plane of line 2—2, Figure 1.

Figure 3 is an enlarged longitudinal vertical sectional view through one end of the 90 steaming board taken in the plane of line 3—3, Figure 2.

Figure 4 is an enlarged top plan of the pedals in their operative relation for controlling the steam supply valve, the steam exhaust 95 valve and the cut-out valve.

Figure 5 is an end view of the several pedal levers and their supporting shafts, together with the adjacent yokes and crank arms on the shafts for operating the yokes. 100

Figure 6 is an end view of one shaft and reversely arranged pedals, together with the adjacent parts of the means for transmitting motion from said pedals to the exhaust valve.

5 Figure 7 is a transverse vertical sectional view taken in the plane of line 7-7, Figure 8.

Figure 8 is a longitudinal vertical sectional view partly broken away, taken in the plane of line 8-8, Figure 5.

10 The steaming board or buck —1— may be mounted in a substantially horizontal position upon any suitable supporting frame or standard adapted to rest upon a floor or other support and comprises a hollow elongated element —2— of cast metal or equivalent material having a steam heated chamber —3— and a steam distributing chamber —4—, the member —2— being tapered longitudinally to conform to the shape of certain 75 classes of clothing such as trousers, skirts and the like which are to be treated.

The steam heated chamber —3— is disposed in a plane beneath the steam distributing chamber —4— and is approximately co-extensive with the surface area of the steaming board but wholly within the marginal edges thereof and is divided by a central lengthwise partition —5—, Figure 2, into opposite lengthwise compartments, said partition extending the major portion of the length of the steaming board but terminates a relatively short distance from the ends thereof to establish communication between the compartments or rather to permit the outflow of the steam through one compartment from the wider end to the narrower end of the steaming board and return through the other compartment to the end of the partition adjacent the wider end of the steaming 90 board for the purpose of maintaining uniform distribution of the steam heat throughout the area of the steam heated chamber.

The end of the partition —5— adjacent the wider end of the steaming board is provided with a rearwardly extending transverse partition —6— united to the rear wall of the heating chamber —3— or rear compartment thereof to form the adjacent end wall of the rear compartment and thereby to cut off direct communication between said rear compartment and wider end of the heating chamber, said transverse partition —6— being arranged in spaced relation to the wider end wall of the heating chamber to form what may be termed the steam receiving end or supplemental compartment —7— of said chamber.

The wider end of the partition —5— is provided with a laterally projecting flange —8— having its front edge curved toward the smaller end of the steaming board and in spaced relation to the front wall of the steam heated chamber —3— to form a connecting passage —9— between the supplemental compartment

—7— and front compartment of said chamber, as shown more clearly in Figure 2.

Steam is admitted to the supplemental compartment —7— through an inlet opening —10— in the bottom thereof, said opening being connected by a pipe to any available source of steam supply.

The partition —6— is provided with an opening —6'— in its bottom thereof some distance to the rear of the openings —10— and —15— to allow drainage of the water from the chamber —7— into the sump —14—.

The wider end wall of the steam heated chamber —3— is provided with a relatively short inwardly projecting central lengthwise partition —12— terminating some distance from the adjacent end of the partition —5— so as to form an intervening steam passage —13— connecting the supplemental chamber —7— with the corresponding end of the front compartment of the chamber —3— so that steam entering the inlet —10— may pass from the supplemental compartment —7— through the passage —13— and thence along the front compartment and return around the opposite end of the partition —5— through the rear compartment to the transverse partition —6—.

The bottom of the end of the rear compartment adjacent the transverse partition —6— is disposed some distance below the bottom of the remaining portions of the chamber —3— to form what may be termed a sump chamber —14— for receiving water of condensation and any foreign matter or 100 impurities carried thereby.

The bottom of the sump chamber is provided with a drainage outlet —15— to which is connected to any suitable source of discharge, not shown, the bottom wall of the chamber —3— being preferably inclined from the narrower end of the steaming board toward the sump chamber —14— to facilitate the drainage of water of condensation from the chamber —3—.

The partition —5— is provided near the bottom wall of the chamber —3— with longitudinally spaced transverse openings —17— to permit steam to pass therethrough from the front compartment to the rear compartment, in addition to the passage of the steam around the end of the partition adjacent the narrower end of the steaming board thus obtaining a more rapid and uniform distribution of the steam throughout the area of the steam heated chamber for quickly heating the walls of the chamber.

The partitions —5—, —6— and —12— and also the top wall of the chamber —3— are preferably formed integral with the element —2—, the lower and upper walls of the heating chamber being supported in fixed relation by said partitions and also by additional tie pieces —18—, as shown in Figure 2.

The steam distributing chamber —4— is

formed in the upper side of the element —2— along the longitudinal center thereof and is relatively narrow transversely but extends the major portion of the length of said element, and, therefore, the major portion of the length of the underlying portion of the chamber —3— so that the top wall of the heating chamber forms the bottom wall of the distributing chamber.

10 It, therefore, follows that the steam entering the distributing chamber will be heated to approximately the temperature of the steam in the heating chamber —3— which is desirable in machines of this character for 15 reducing the moisture content of the steam which is applied to the articles to be treated.

The distributing chamber —4— is provided with a substantially flat and rectangular top wall or plate —19— preferably of sheet metal substantially co-extensive with the area of said chamber except that its marginal edges extend beyond the walls of the chamber and are secured by screws or equivalent fastening means to the marginal walls of the distributing chamber, said plate —19— being provided with a series of relatively small steam exits as shown in my pending application referred to.

10 The steam distributing chamber —4— is divided intermediate its ends by a transverse partition —23—, Figure 5, thereby forming opposite end compartments to which steam may be supplied in a manner hereinafter described so that both compartments may be 15 used for supplying steam to a garment on the plate —19— or steam may be supplied to one of the compartments independently of the other compartment when operating upon relatively small articles or small portions of 20 larger articles thus permitting the economic conservation of the steam and reducing the liability of escape of excessive steam into the room in which the machine is located.

This larger end of the partition —5— is 25 provided with a vertical opening —24— extending through the bottom of the element —2— and connected by a pipe —25— to a suitable exhaust device, presently described, the upper end of said opening —24— being 30 in open communication with one end of a branch passage —26— having its other end communicating with a depressed passage —27— in the lower wall of the distributing chamber —4—, as shown in Figure 3.

That is, the passage —27— is depressed below the level of the remaining portions of the distributing chamber —4— while the branch passage —26— is depressed below the plane of the passage —27— so that the 35 opening —24— leads from the lower part of the passage —26—.

A horizontal partition plate —28— is secured by screws or other fastening means to the upper face of the top wall of the steam heated chamber —3— and extends to the end

of the chamber —2— nearest the large end of the steaming chamber in spaced relation to and preferably parallel with the overlying portion of the top plate —19— so as to form the bottom of the compartment as —4'— of the distributing chamber —4—.

The plate —28— forms the top wall of the passages —27— and —26— and is provided with an opening —30— registering with the inner enlarged end of the partition —12— 75 near the wider end of the steaming board, Figure 3.

A baffle plate —31— is secured to the upper face of the bottom wall of the passage —27— to extend across the upper end of the opening —24— and also to form a part of the top wall of the branch passage —26— which communicates with the passage —27— through an opening —32— at the inner end of the baffle plate —31—.

The partition —12— is provided with a vertical opening —33— in which is secured a bushing —34—, Figure 3, the opening —33— and bushing —34— being arranged in vertical alinement with the opening —30— 80 in the partition plate —28— and extending from the underside of the adjacent portion of the element —2— across the adjacent portion of the chamber —3—.

The opening or port —30— serves to connect the adjacent end of the passage —27— with the compartment —4'— of the distributing chamber —4— and is controlled by a valve —35— which is movable in the upper end of the opening —33— and adjacent portion of the passage —27—, as shown in Figure 3, for a purpose hereinafter described.

The portions of the bottom and top walls of the steam heated chamber —3— between the adjacent ends of the partitions —5— and —12— are provided with vertically registering openings in which is tightly secured the hollow stem —36— of a valve case —37— so that the valve stem may extend across the chamber —3—, the upper end of the stem —36— being threaded and engaged in a threaded aperture in the upper wall of the chamber —3— while the lower end of said stem is threaded and engaged by a lock nut —38— which, in turn, engages the lower face of the adjacent portions of the member —2— to firmly hold the valve case —37— in operative position.

This valve case is provided with two upright interior passages —39— and —40— separated by an upright partition —41— which extends upwardly from the bottom of the valve case —37—.

The upper end of the passage —39— is provided with an inlet port —42— opening directly into the steam heated chamber —3— while the upper end of the other passage —40— is provided with an outlet port —43— communicating directly with the adjacent portion of the passage —27—, Figure 3.

The lower portion of the partition —41— is provided with a port —44— connecting the adjacent portions of the passages —39— and —40— and controlled by a horizontal valve —45—, Figure 3, which is normally closed by a coiled spring —46— and is adapted to be opened at will by mechanism presently described.

10 *Steaming means*

The valve —45— controls communication between the passages —39— and —40— and in view of the fact that steam is maintained in the chamber —3— for heating purposes it is evident that if the valve —45— is opened the steam from said chamber will pass from the passage —39— through the open port —44— and thence through the passages —40— and —43— into the passage —27— and 15 thence into the distributing chamber —4— where it is free to escape through the perforated plate —19— to the article under treatment on the upper surface of the steaming board.

20 That is, when the valve —45— is opened the steam from the chamber —3— may pass into the passage —27— and thence through the passage —29— and —30— into the steam distributing compartments —4— and —4'— providing the valve —35— is in its open position.

25 It is obvious, however, that if the valve —35— is adjusted to close the port —30— the steam admitted to the passage —27— will escape to the compartment —4— through the outlet of the passage —27— at the corresponding side of the transverse partition which then prevents the passage of the steam into the compartment —4'— as shown in my pending application.

30 Both of these valves —35— and —45— and also the exhaust controlling valve are under the control of the operator in a manner hereinafter described and, it, therefore, follows that the steam may be directed to both of the compartments —4— and —4'— simultaneously when the valves —35— and —45— are opened but when the valve —35— is closed the steam from the chamber —3— will be 35 discharged only into the compartment —4—.

The portion of the bottom of the steam heated chamber —3— immediately surrounding the valve stem —36— is made in the form of a pyramid —36'— to break the capillary action or suction of water up through the valve —37— and thereby assists in maintaining a substantially dry buck.

35 Each compartment —4'— and —4— of the distributing chamber —4— controls about one-half of the surface of the steaming board and inasmuch as the valve —35— is used to cut off communication between the steam passage —27— and compartment —4'— it may be technically termed a half-valve in 40 that it controls one-half of the steaming area

while the other valve —45— may be termed the steaming valve for the reason that it controls the supply of steam to both of the compartments —4— and —4'— when the valve —35— is opened or when the valve —35— is closed controls the supply of steam to the compartment —4'— independently of the compartment —4—.

The exhaust of the steam and moisture from the article under treatment is also controlled by a valve —47—, Figure 1, under the control of the operator in a manner herein-after described.

The self-closing valves —45— and —47— and the self-opening valve —35— are adapted to be operated independently of each other or in certain combinations by somewhat similar mechanisms including a plurality of, in this instance three, similar double pedal levers —48— and —49— and —50— centrally fulcrumed adjacent each other and having their opposite arms provided respectively with similar pedals marked —S—, —H— and —D— which are arranged in sequence but in reverse order at opposite sides of their fulcrums to enable the operator to selectively and successively operate the corresponding valves in the same order from either side the machine, as shown more clearly in Figure 1, and Figures 4 to 8 inclusive.

45 It may be stated here that the openings —17— and —6'— in the partitions —5— and —6— respectively are made primarily for the purpose of connecting the cores for the adjacent chambers in the process of casting the steaming board and incidentally serve as drainage openings to facilitate the drainage of water of condensation along the bottoms of the chambers —3— and —7— to the sump chamber —14— and drainage outlet —15— leading therefrom.

50 These pedal levers —48—, —49— and —50— are respectively secured to the front ends of a corresponding number of longitudinally extending shafts —51—, —52— and —53— which are journaled in suitable bearings in the lower portion or base of the pedestal —2—, Figure 1.

55 It will be noted upon reference to Figure 4 that the pedal levers —48—, —49— and —50— are arranged in such manner that the pedals —S—, —H— and —D— at the front side of the machine will be arranged in sequence from the right hand to the left hand of said machine while the corresponding pedals at the rear of the machine will be arranged in reverse order or from the left hand toward the right hand of the machine so that the pedals will be arranged in the same order with reference to the position of the operator at the front side or at the rear side of the machine, it being understood that the garments under treatment may be operated upon with equal facility from either side of the machine.

These pedal levers are preferably located in planes approximately midway between the front and rear sides and also approximately midway between the ends of the steaming board and together with the major portion of the steaming board are located in a vertical plane mainly at the right hand side of the pedestal —2— so as to afford ample space between the pedals and steaming board for the manipulation of the pedal levers.

The shaft —51— upon which the pedal lever —48— is mounted is tubular to permit the passage of the shaft —53— therethrough and extends longitudinally through the major portion of the base of the pedestal —2— and is provided with oppositely projecting similar crank arms —54— disposed in approximately the longitudinal and transverse vertical planes of or directly below the valve case —37— for engaging the opposite arms of a saddle yoke —55— at opposite sides of the axis of the shaft.

The yoke —55— is provided with a central vertical slot —55'— extending upwardly from the bottom thereof so as to straddle the shafts —51— and —52—, said slot being extended upwardly a sufficient distance above the shaft —52— to permit the necessary vertical movement of the yoke by the rocking of the arms —54— without interfering with the shaft —52—.

The side walls of the slot cooperate with opposite sides of the shaft —51— to guide the yoke —55— in its vertical movement and also to keep the outer ends of the opposite sides of the yoke in alignment with the adjacent ends of the crank arms —54—, the opposite arms of the yoke —55— adjacent the hub of the arms —54— being slotted vertically from the bottom upwardly to receive said arms.

It is now evident that the downward pressure upon either of the pedals —S— will effect a corresponding rocking movement of the tubular shaft —51— and crank arms —54— carried thereby and that this rocking movement in either direction of the crank arms —54— will effect a corresponding vertical movement of the yoke —55—.

This yoke —55— is connected by a vertical rod —56— to one arm of a bell-crank lever —57— which is pivoted at —58— to the underside of the valve case —37—, as shown in Figure 3, and has its other end engaged with one end of another bell-crank lever —59—.

The lever —59— is pivoted at —59'— to the underside of the valve case —37— and its other shorter arm engaged with a plunger —60— which is guided in a bushing in the adjacent side of the valve case —37— in alignment with the valve —45— for opening said valve as the levers —57— and —59— are rocked about their respective pivots by the upward movement of the rod —56—.

This opening movement of the valve —45— permits the passage of steam from the steam heated chamber —3— into the chamber —27— and thence into the distributing chamber —4— throughout the entire area thereof to escape through the perforated top plate —19— of the steaming board in the manner previously described.

Half steaming

The shaft —52— which controls the operation of the half-valve —35—, Figure 3, is disposed in a plane above or directly over the shafts —51— and —53— and carries at one end the pedal ends —H— which are disposed in a vertical plane between the corresponding pedals —S— and —D— which normally are in a horizontal plane slightly above the adjacent pedals —S— and —D—, as shown in Figure 1, so that either of the pedals —H— may be operated by the foot of the operator simultaneously with the operation of either of the pedals —S— or —D— at the same side for closing the normally open valve —35— when it is desired to cut off the supply of steam to one of the compartments as —4'— and to supply steam to the other compartment as —4— of the distributing chamber, thus permitting the use of approximately half of the surface of the steaming board for steaming relatively small garments or small portions of larger garments.

The other end of the shaft opposite the pedal end is provided with a pair of oppositely projecting crank arms —61— adapted to engage opposite arms of a yoke —62— similar to the yoke —55— but somewhat shorter vertically by reason of the fact that the shaft —52— is supported above the shaft —53—.

The yoke —62— is supported on the lower end of a vertically movable rod —63—, Figure 1, and has its upper end provided with a head —64— having a vertical guide opening —64'— therein for the reception of the lower end of a valve stem —65— which carries at its upper end the half valve —35— as shown in Figure 7.

The valve stem —65— is yieldingly supported on the head —64— to allow a limited upward movement of the rod —63— and yoke —62— carried thereby after the valve —35— has been closed to assure a positive closing of the valve and for this purpose the valve stem —65— is provided with a shoulder —66— and coiled springs —67— and —67'—.

One of the springs —67— is interposed between the shoulder —66— and upper end of the head —64— while the other spring —67'— is interposed between said shoulder —66— and the lower end of the bushing —35—.

It is now clear that if it is desired to utilize only a part of the surface of the steaming board for steaming purposes as, for example,

the part which is registered with the compartment —4— either one of the pedals

—H— may be depressed by the foot of the operator simultaneously with the adjacent pedal —S— thereby opening the valve —45— and closing the valve —35—, the opening of the valve —45— serving to admit steam to the distributing compartment —4— while the closing of the valve —35— will prevent the entrance of steam from the chamber —27— to the distributing compartment —4'—, as previously explained.

Drying device

15 This drying device including the valve —7— is controlled by the pedals —D— through the medium of the shaft —53— which extends from the pedals entirely through and beyond the tubular shaft —51— 20 and is provided with oppositely projecting crank arms —68— adapted to engage the opposite arms of a yoke —69— similar to the yokes —55— and —62—.

The yoke —69— is secured to the lower 25 end of an upwardly projecting rod —70— having its upper end connected to a lever —71— which, in turn, is pivoted at —71'— to a bracket on the valve case —47—, and has its other end adapted to engage the stem 30 —72— of the valve within the case —47— for opening said valve when the rod —70— is moved upwardly by the turning movement of the shaft —53— in either direction.

35 The valve case —47— and valve therein is of the self-closing type and is connected to a steam supply pipe —73— to which steam may be supplied from any available source.

40 The outlet side of the valve case —47— is connected by a pipe —74— to the inlet side of a T-pipe —75— having an exhaust pipe —76— adapted to be connected to any suitable waste or soil pipe, not shown.

45 This T-coupling is connected to the lower end of the exhaust pipe —25— which, in turn, is connected to both compartments —4'— and —4— of the distributing chamber —4— through the openings —30— and —27—, Figure 3, so that when the valve —47— is opened by one or the other of the 50 corresponding pedals —D— steam will pass through the pipes —73—, and —74— and thence through the T-coupling —75— and outlet pipe —76— across the lower end of the pipe —25— thereby creating more or 55 less suction in the pipe —25— to withdraw steam and moisture from the distributing chamber —4—.

60 Or, if the steam is used in the compartment —4— only for moistening purposes the steam and moisture may be withdrawn therefrom independently of the compartment —4'— by simply closing the valve —35— simultaneously with the opening of the valve —47— which may be accomplished 65 by the simultaneous depression of adjacent

pedals —D— and —H— by the foot of the operator.

Operation

If, in the operation of the steaming board, 70 it is desired to utilize the entire surface of the steaming board for moistening purposes it is simply necessary to depress one or the other of the pedals —S— which through the medium of its connections with the plunger 75 —60— will open the valve —45— thereby allowing steam to pass from the heating chamber —3— through the passages —39— and —40— and thence through the passages —27— and —30— into the distributing 80 chamber —4— from which the steam is discharged through the perforated plate —19— and into the garment on the surface of the steaming board.

If it is desired to introduce steam into the 85 compartment —4— of the distributing chamber —4— independently of the compartment —4'— it is simply necessary to depress one or the other of the pedals —S— and the adjacent pedal —H— which through the medium of its connections with the valve —35— will cause said valve to close the port —30— thereby cutting off communication between the steam chamber —27— and steam distributing compartment —4'—, it being understood 95 that the steam is then free to escape into the compartment —4— at the corresponding side of the transverse partition, the latter serving to prevent the passage of steam from the compartment —4— to the compartment —4'—.

When it is desired to exhaust the steam and moisture from the article under treatment on the surface of the steaming board it is simply necessary to depress one or the other of the pedals —D— which through the medium of its connection with the valve —47— will open said valve, thereby allowing the steam to discharge across the lower end of the exhaust pipe —35— for creating 105 suction therein sufficient to withdraw the steam and moisture from the distributing chamber —4— and to discharge the same through the pipe —76— of the T-coupling —75—.

110 After the steam has been used in the compartment —4'— only for moistening purposes one or the other of the pedals —H— may be depressed simultaneously with the depression of the adjacent pedal —D— for closing the valve —35— and thereby directing the suction entirely to the compartment —4—.

115 Owing to the fact that the pedals —H— are disposed in a plane slightly above and between the normal planes of the adjacent pedals —S— and —D— it is evident that the pedal —H— will be operated to close the valve —35— just ahead of the opening of the steaming controlling valve —45— or exhaust 120

115

120

125

130

valve —47—, this operation being of considerable importance in the use of the machine for the reason that it is desirable to close the valve —35— just preceding the admission of steam into the compartment —4— and for the further reason that it is desirable to close the valve —35— just preceding the opening of the valve —47— for exhaust purposes.

Although I have described in detail the various parts of the garment steaming machine it will be evident that many of these details may be changed without departing from the spirit of the invention.

What I claim is:

1. The combination with a steaming board, a supporting base therefor, and a steam controlling valve of a valve operating rod reciprocally movable endwise vertically, a yoke secured to the lower end of the rod and provided with oppositely extending arms, a rocker shaft journaled on said base and movable about an axis intersecting the axis of the rod, said rock shaft being provided with crank arms extending in opposite directions therefrom along the arms of the yoke for engaging adjacent arms of said yoke as the shaft is rocked in reverse directions for moving the valve-operating rod in one and the same direction, and a pair of pedals secured to and projecting laterally in opposite directions from the shaft for rocking said shaft in reverse directions.

2. The combination with a steaming board having a supporting base and a steam controlling valve, of a valve-operating rod reciprocally movable endwise vertically, a yoke secured to the lower end of the rod and provided with oppositely extending arms, a rocker shaft journaled on said base and movable about an axis intersecting the axis of the rod and provided with crank arms extending in opposite directions therefrom along the arms of the yoke for engaging adjacent arms of the yoke as the shaft is rocked in reverse directions for moving the valve-operating rod in one and the same direction, and a pedal lever secured intermediate its ends to the rocker shaft to extend in opposite directions therefrom and having its outer ends provided with pedals for rocking the shaft in reverse directions when either pedal is depressed.

3. In a machine of the character described, a valve-operating rod reciprocally movable endwise and provided with out-bearings at opposite sides of its axis, a rock-shaft having oppositely projecting crank arms extending across said bearings for alternatively engaging the latter as the shaft is rocked in reverse directions and thereby moving the rod endwise, and a pair of pedals secured to and projecting in opposite directions from the shaft for rocking said shaft in reverse directions.

4. In a machine of the character described, a valve-operating rod reciprocally movable

endwise, a rock shaft extending across the axis of the rod and provided with oppositely projecting pedal arms having their pedals movable in different planes about the axis of the shaft for rocking the shaft in reverse directions and means actuated by the movement of the shaft in either direction for moving the rod endwise.

5. In a machine of the character described, two valve-operating levers pivoted intermediate their ends to rock about a common axis and crossing each other so that their outer ends at opposite sides of their respective axes will be arranged in reverse order.

6. In a machine of the character described, two valve-operating levers pivoted intermediate their ends to rock about parallel axes and crossing each other so that their outer ends at opposite sides of their respective axes will be arranged in reverse order.

7. In a machine of the character described, separate valve-operating rods each having oppositely projecting arms, and relatively rotatable co-axial rock shafts one for each rod and each having oppositely projecting crank arms for engaging the arms of the corresponding rod, each rock shaft having a pair of oppositely projecting pedals for rocking the same in reverse directions.

8. The combination with a steaming board having a supporting base and separate steam-controlling valves, of relatively rotatable co-axial rock-shafts mounted on the base one within the other and each provided with a pair of oppositely projecting crank-arms and a pair of oppositely projecting pedals, and separate devices for transmitting motion from each pair of crank-arms to one of the valves as the corresponding shaft is rocked in reverse directions by its pedals.

In witness whereof I have hereunto set my hand this twenty-eight day of January, 1930.

HERBERT G. BEEDE.
